FOLDING CARTON

Frank Charles Shina, Thomson, N. Y., assignor
to United Board & Carton Corporation, New
York, N. Y., a corporation of New Jersey

Application September 18, 1946, Serial No. 697,638

2 Claims. (Cl. 229—37)

1

This invention relates to improvements in folding cartons and particularly to improvements in end closures for such cartons. The object of my invention is to provide a simple end closure, integral with the side walls of the carton which can be easily and simply opened and closed, which gives rigidity to the carton and which may or may not be used with adhesive. My invention is particularly, although not exclusively, adapted for use with a hexagonal carton and I shall illustrate and describe it in connection with such a one. Thus in the accompanying drawings which disclose a preferred embodiment of my invention.

Figure 1 is a perspective view of a hexagonal carton equipped with the end closure of the present invention.

Figure 2 is a top view of the carton shown in Figure 1.

Figure 3 is a view of the single piece of material or blank from which my carton is made up, shown flat and unfolded, and

Figure 4 is a perspective view of the upper end of my carton with the closure open, but in position to be inserted and closed.

The folding carton illustrated in these drawings has, when folded, the shape of a right hexagonal prism the side panels or walls of which are all of the same size, and is provided with recessed end closures. The whole is folded up from a single blank of cardboard or other similar light, stiff material, as shown in Figure 3. The six side panels 1 are defined by scoring, indicated by dot and dash lines, along which the blank is bent to form the carton. A longitudinal flap 2 along the edge of the sixth panel is designed to be glued to the under face of the first panel to form the completed hexagonal prism, as shown best in Figure 2. The end closures are formed from trapezoidal sections 3 and 3a, each having four integral flaps 4, 5, 6, and 7 and 4a, 5a, 6a, and 7a, respectively, all scored for folding, as indicated.

The flap 4 joins and is integral with the third panel and the flap 4a joins and is integral with the sixth. A pair of similar, but unnumbered, closure sections with similar flaps extend from the lower edge of the blank to form a bottom closure.

To form the carton, the prismatic body is formed, as already explained, by folding the blank along the score lines and gluing flap 2 to the under face of the first panel. The flaps 4, 5, 6, 7, 4a, 5a, 6a, and 7a—and their counterparts on the bottom closure—having been folded along their score lines, as indicated in Figure 2, the

two long central flaps 6 and 6a are grasped and held together by thumb and forefinger, as shown in Figure 4, and the closure pushed downward into the end of the carton until the parts assume the position shown in Figures 1 and 2. The closure is opened by pulling upwardly on the flaps 6 and 6a.

When the end closures are closed a strong, rigid carton is formed. The closure flaps may be glued to the side wall panels of the body, but if the parts are carefully proportioned the closure may be held closed for most purposes merely by frictional engagement of the flaps with the side walls of the carton and with each other. The two middle flaps together form an upstanding rib which not only serves as a convenient handle for use in opening and closing the carton, but also serves to add rigidity to the structure.

I claim:

1. In a carton of the character described, a plurality of joined side walls having free edges at one end thereof, a sectional end wall arranged substantially normal to said side walls and spaced inwardly from said free edges, said end wall comprising complementary halves having meeting edges, a flap integrally joining each half to one of said side walls, and a flap integrally joined to each half along said meeting edges, said last mentioned flaps on the respective halves cooperating to define a reinforcing rib on the exterior surface of said end wall.

2. In a carton of the character described, a plurality of side walls having free edges at one end thereof, a sectional end wall comprising complementary halves, each of said halves having a joining edge and a meeting edge, said edges being substantially parallel, a flap integrally joined to each joining edge of one of said halves and integrally joined to one of said side walls, and a second flap integrally joined to said meeting edge of each half, said last mentioned flaps cooperating to define a reinforcing rib on the exterior of said end wall.

FRANK CHARLES SHINA.
